(57) **CLAIM**

The ornamental design for a display screen or portion thereof with graphical user interface, as shown and described.

DESCRIPTION

FIG. 1 is a front view of a display screen or portion thereof with graphical user interface showing a first image of a first sequence of our design; and

FIG. 2 is a second image thereof.

FIG. 3 is a front view of a display screen or portion thereof with graphical user interface showing a first image of a second sequence of our design; and

FIG. 4 is a second image thereof.

FIG. 5 is a front view of a display screen or portion thereof with graphical user interface showing a first image of a third sequence of our design; and

FIG. 6 is a second image thereof.

FIG. 7 is a front view of a display screen or portion thereof with graphical user interface showing a first image of a fourth sequence of our design; and,

FIG. 8 is a second image thereof.

The outermost broken lines show a display screen or portion thereof that forms no part of the claimed design. The other broken lines show portions of the graphical user interface which form no part of the claimed design.

The appearance of the front view of the display screen or portion thereof with graphical user interface in the first, second, third, and fourth sequences sequentially transition between the images shown in FIGS. 1-2, 3-4, 5-6, and 7-8, respectively. The process or period in which one image transitions to another forms no part of the claimed design.
